United States Patent Office.

ANDREW LITTLE, OF NEW YORK, N. Y.

Design No. 4,673, dated February 21, 1871.

DESIGN FOR TYPE.

The Schedule referred to in these Letters Patent and making part of the same.

I, ANDREW LITTLE, of the city, county, and State of New York, have invented and produced a new and original Design for Printing-Type, of which the following is a specification.

The nature of my design is fully represented in the accompanying typographic impressions, to which reference is made.

I claim as my invention—
The design for printing-type, as shown.
ANDREW LITTLE.
